ATTORNEY

UNITED STATES PATENT OFFICE

IRVING S. BODKIN, OF NEW YORK, N. Y., ASSIGNOR, BY MESNE ASSIGNMENTS, TO GILLETTE SAFETY RAZOR COMPANY, OF BOSTON, MASSACHUSETTS, A CORPORATION OF DELAWARE

SAFETY RAZOR

Application filed September 26, 1929. Serial No. 395,225.

My invention relates to improvements in safety razors, and has particular reference to the class of safety razors in which a flexible blade is clamped between two members for shaving.

An object of my invention is to retain a blade on one of the razor members, such as the guard member, when the members are separated, so that the blade will not be dislodged from the member by tipping or shaking of said member, and whereby wiping of the blade while upon said member is facilitated.

Another object is to cause the razor member that is not provided with the blade-retaining means to resist sliding of the blade between the members in a longitudinal direction.

My invention comprises novel details of improvement that will be more fully herein-
20 after set forth and then pointed out in the claims.

Reference is to be had to the accompanying drawings in which,

Fig. 1 is an end view of a safety razor embodying my invention;

Fig. 2 is a section on line 2, 2 in Fig. 1;

Fig. 2a is an end view looking from the right hand side of Fig. 2;

Fig. 3 is a plan view of the blade;

Fig. 4 is a plan view of the razor assembled for use with backing member partly broken away;

Fig. 5 is a plan view of the guard member;

Fig. 6 is a plan view illustrating applica-
35 tion of the blade to the guard member, or removal of the blade therefrom;

Fig. 7 is a plan view illustrating the blade in shaving position upon the guard member;

Fig. 8 is a section on line 8, 8 in Fig. 7;

Fig. 9 is a section on line 9, 9 in Fig. 4, before the members are clamped against the blade for shaving;

Fig. 9a is a section similar to Fig. 9, show-
45 ing the parts in shaving position;

Fig. 10 is a section on line 10, 10 in Fig. 1;

Fig. 11 is a section on line 11, in Fig. 7, and

Fig. 12 is a modification showing blade re-
50 tained on clamping member instead of guard member.

Similar numerals indicate corresponding parts in the several views.

At 1 is a guard member for blade 2, said member having comb-like teeth 1a for the blade edges. At 3 is a backing member for 55 the blade. Any well known or desired means may be provided for clamping the members 1 and 2 against the blade. I have shown member 3 provided with a threaded stud 4 adapted to pass through an opening 5 in the 60 blade and through an opening 6 in member 1, which stud is adapted to engage a threaded opening 7 in a handle 8, (Fig. 2), for clamping the parts 1, 2 and 3 together for shaving.

One of the razor members, such as the 65 guard member 1, is provided with studs 9 and 10, projecting from the blade-receiving side of the member, adapted to enter openings 5a in the blade that are spaced on opposite sides of the central opening 5, when the 70 blade is laid upon said member, as illustrated in Fig. 6. At 11 is a relatively narrow elongated rib upon member 1, shown extending longitudinally along the member from the stud 10 toward the adjacent end of the mem- 75 ber, and adapted to enter the longitudinal slot 12 in the blade that extends between the openings 5 and 5a, said slot and openings being in open communication, (Fig. 3). The

openings 5a in the blade are elongated or 80 slotted towards the adjacent ends of the blade, at 13. The studs 9 and 10 and the blade open- 85 ings 5a are complementary and are wider than the slot 12 and the slotted portions 13 of the blade in a transverse direction or toward the guard teeth and the cutting edges of the blade, so that when the blade is laid upon member 1 the studs will pass through the openings 5a and the rib 11 will project into the slot 12, (Fig. 6). The studs 9 and 10, on 90 their sides toward the guard teeth, are under- cut, at 9a and 10a, (Figs. 8 and 9) so that the narrow parts of the studs will receive the slot 12 of the blade, the studs thereby being what may be termed headed, to overlie adjacent 95 edge portions of the blade in shaving position. When the blade is slid along the mem- 100 ber 1, from the position in Fig. 6 to the shaving position in Fig. 7, the blade openings 5a will pass away from the studs and the latter

will enter the slot 12 of the blade, and the outer overlying or headed portions of the studs that extend over the blade will retain the latter on member 1, (Fig. 9). The outer 5 end of rib 11 is shown undercut or reduced angularly to receive the adjacent slot portion 13 of the blade in shaving position of the latter to limit sliding and lifting of the blade, (Fig. 2). The member 1, at the end opposite 10 the rib 11, is shown provided with an up-standing lug 14, that is undercut or reduced angularly, to receive a notch or recess 15 at the adjacent end of the blade in shaving position, (Fig. 2). The blade openings 5a, the 15 slots 12 and 13, and the notches or recesses 15 at both ends of the blade, are symmetrical- 20 ly disposed respecting the longitudinal axis of the blade, so that the blade may be reversed end for end upon member 1, with either face 25 of the blade against said member, so that the studs, the slots 12 and 13, and the lug 14, will cooperate appropriately with the blade to retain it upon said member.

The backing member 3 is shown provided 25 with a projection 16, extending toward the blade to enter the notch 15 at the adjacent end of the blade to prevent outward endwise movement of the blade before being clamped. The members 1 and 3 are shown curved in a 30 transverse direction to clamp the blade in a curved position for use, (Fig. 9a). The curvature of the inner face of member 3 is on a shorter radius than the curvature of the outer face of member 1, providing a hollow 35 space under member 3 in which the studs 9 and 10 are received when the members 1 and 3 are clamped against the blade for shaving with the outer edges of the member 3 bearing against the blade. At the ends of member 3, shown adjacent to the corners, are 40 lateral projections 17, spaced apart, that are adapted to extend beyond the adjacent end portions 18 of the blade, and to bear against the projecting portions 19 at the ends of the 45 blade. The studs 9, 10 and the bar 11 will keep the blade in shaving position on member 1, with the cutting edges of the blade in shaving relation to the guard teeth, and the projections 17 of the backing member 3, 50 by engagement with the portions 19 of the blade, will keep the member 3 in proper shaving position upon the blade.

When the blade has been laid upon member 1, as in Fig. 6, and is slid along said member to the shaving position in Fig. 7, the studs 9, 10 and the bar 11 will guide the blade and keep it from edgewise displacement and in proper position, and so that the blade will not fall off the member during 55 proper handling, the blade then being in position to receive the backing member upon it. The member 3 will be guided to proper position upon the blade by the projections 17 engaging the appropriate parts of the blade, 60 with the stud 4 passing through the openings

5 and 6 to receive the handle. When the handle is screwed on stud 4 the parts will retain their relative positions, since the blade cannot shift edgewise relatively to the studs 9, 10 and the bar 11. When the backing member 3 is removed the blade will be exposed upon the member 1 and may be wiped on top thereof without being dislodged therefrom. the studs 9 and 10 and the blade openings 5a are shown substantially in corresponding diamond-like shape whereby they are elongated transversely of the blade so that the headed portions of the studs may overlie the metal at the sides of slot 12 to keep the blade down on the member 1 in use and while 70 cleaning and handling. When the members 1 and 3 are clamped against the blade the edges of the latter along the slot 12 are resisted by the overlying headed portions of the studs 9 and 10, thereby preventing the 75 metal along the slotted portion of the blade from bending outwardly under the bending strain, and reducing danger of the metal of the blade at the end portions aligned with the slot from breaking. The construction of the 80 blade provides for increased flexibility and enables a thicker blade to be provided than the 85 so-called wafer blades in use.

Having now described my invention what I claim is:

1. A safety razor comprising blade clamp- 90 ing members having transversely curved blade clamping surfaces, and means to retain said members upon a blade, one of said members having headed studs to enter openings 100 and a slot entirely within the blade to retain the blade upon said member.

2. A safety razor as set forth in claim 1 in which the member having the studs is pro- 105 vided with a bar to enter an opening and the slot of the blade.

3. A safety razor comprising blade clamp- 110 ing members having transversely curved blade clamping surfaces, and means to retain said members upon a blade, one of said members having headed studs and having a bar narrower than the heads of the studs ex- 115 tends longitudinally along said member to enter openings and a slot entirely within the blade to retain the blade upon said member.

4. A safety razor as set forth in claim 3 in which the outer end of the bar is reduced to receive a slotted portion of the blade at one of the openings.

5. A safety razor comprising blade clamp- 120 ing members having transversely curved blade clamping surfaces, and means to retain said members upon a blade, one of said members having headed studs that are elongated transversely of the member to receive open- 125 ings in the blade corresponding thereto, said studs being arranged to receive a slot in the blade and to overlie the blade adjacent to said slot to retain the blade upon the member.

6. A safety razor as set forth in claim 5 in 130

which the member having the studs is provided with a bar to enter the slot in the blade.

7. A safety razor comprising blade clamping members having transversely curved blade clamping surfaces, and means to retain said members upon a blade, one of said members having a longitudinal bar having a reduced outer end to receive a slot in the blade and to engage a portion of the blade at the end of the slot.

10 8. A safety razor comprising blade clamping members having transversely curved blade clamping surfaces, and means to retain said members upon the blade, one of said members having a lug adjacent to one end thereof, said lug having a reduced inner portion to receive an adjacent outer end of the blade.

9. A safety razor comprising blade clamping members having transversely curved blade clamping surfaces, and means to retain said members upon a blade, one of said members having headed studs to retain a blade upon said member, the other member having projections to engage the blade to retain the said member in operative position upon the blade.

10 10. A safety razor as set forth in claim 9 in which the member having the projections is provided with another projection to oppose the blade to keep it from sliding.

11. A safety razor comprising blade clamping members having transversely curved blade clamping surfaces, means to retain said members upon a blade, one of said members having headed studs, and a blade having spaced openings and having a slot communicating with said openings entirely within the blade to receive said studs, narrow portions of the studs receiving the blade slot and the headed portions of the studs overlying the metal of the blade along the slot when the blade is in shaving position respecting the second named member.

12. A safety razor as set forth in claim 11 in which the second named member is provided with a bar to enter the slot of the blade.

13. A safety razor as set forth in claim 11 in which the said member is provided with a lug to engage an end portion of the blade.

14. A safety razor as set forth in claim 11 in which the said member is provided with a lug having a reduced portion and the blade has a recess at its ends to receive said lug.
